SAFETY RAZOR

John D. Garretson, Oakland, Calif.

Application October 14, 1930. Serial No. 488,597

7 Claims. (Cl. 30—12)

This invention relates to a safety razor.

It is well known in connection with safety razors that most of the same include a head provided with a blade seat and clamping member between which elements the blade is interposed. A suitable handle is provided in association with the head and suitable means is also provided for retaining the whole in applied position.

10 The primary object of this invention is to provide a safety razor, the parts of which can be cleaned without necessitating the disassembly of all of the parts of the razor, and without the removal of the clamping member, the blade, and handle.

Another object of the invention is the provision of a safety razor the clamping member or holder of which may be fixedly held in spaced relation above the razor seat to allow the cleaning of the parts without removing the clamping member or the blade, the clamping member being also supported so as to allow the turning of the same into an inverted position to permit the replacement of the razor blade, without disassembly of the entire safety razor.

Other objects and advantages are to provide a safety razor that will be superior in point of simplicity, inexpensiveness of construction, positiveness of operation, and facility and convenience in use and general efficiency.

In this specification and the annexed drawing, the invention is illustrated in the form considered to be the best, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing wherein,

Fig. 1 is a sectional view of a safety razor constructed in accordance with my invention.

45 Fig. 2 is a top plan view of the safety razor.

Fig. 3 is a side view of the safety razor, part of the handle being broken away.

Fig. 4 is a fragmental side of the safety razor, showing the clamping member in elevated position.

Fig. 5 is a fragmental side view of the safety razor showing the clamping member in inverted position.

55 Fig. 6 is an elevational view of the safety razor, a portion of the handle being broken away.

A safety razor constructed in accordance with my invention includes a head 6 and a handle 7.

The head 6 includes a substantially concavo-convex blade seat 8 from the center of which the handle 7 extends and upon the convex, upper side 60 of which a razor blade 9 is positioned. As in the conventional construction of safety razors, the side edges of the blade seat 8 are provided with serrations or teeth 11. A clamping member 12 fits over the convex side of the blade seat 8 to 65 hold the razor blade 9 in place.

Adjacent the opposite ends of the blade seat 8 are apertures 13 into which slidably fit guide bars 14. The clamping member has a boss 16 extended from each end thereof. The bosses 16 are in alignment with each other and are disposed in continuation of the longitudinal center line or axis of the clamping member 12. From each boss 16 extends a pivot pin 17 journaled in the upper end of the adjacent guide bar 14. In this manner 70 the clamping member 12 is journaled in the upper ends of the guide bars 14 and is held by the latter in alignment with the convex face of the blade seat 8. It is to be noted that the bars 14 are outside of the end of the blade 9 and do not extend therethrough, thereby to allow the movement of the blade 9 with the clamping member 12 as the latter is turned around its longitudinal axis into inverted position.

80 The handle 7 is hollow and it extends from the convex surface of the blade seat 8 through the seat 8 and beyond the concave face of the seat, as shown. Inside of the hollow handle 7 is rotatably disposed a tube 18. The free end of the handle 7 is reduced at 19, and the extremity of the reduced handle end 19 is exteriorly threaded to receive an interiorly threaded bushing 21 thereon. The bushing is spaced from the shoulder 22 of the reduced end 19 to form a retaining groove 85 thereat. The free end of the tube 18 is enlarged at 23 and it abuts against the end 19 and against the bushing 21. A retaining bushing 24 surrounds the entire head 23 and extends into the groove between the bushing 21 and the shoulder 90 22. The retaining bushing 24 is fixed to the tube 22 by means of set screws 26. In this manner the tube 18 is held against axial movement in the handle 7 with freedom of rotary movement.

95 The inner end of the tube 18 is interiorly threaded and it abuts against a shoulder 27 within the handle 7. A threaded stem 28 extends from the center of the clamping member 12 into engagement with the inner end of the tube 18. The stem 28 is slidable through the end of the 100 handle 7. By rotating the bushing 24 the tube 105 22 is held against axial movement in the handle 7 with freedom of rotary movement.

110 Fig. 6 is an elevational view of the safety razor, a portion of the handle being broken away.

18 is rotated. Inasmuch as the stem 28 is held against rotation by the clamping member 12, it is advanced axially by the rotating tube 18. Thus the clamping member 12 can be elevated and held 5 in spaced relation above the convex face of the seat 8, whereby the cleaning of the safety razor is permitted without disassembling the safety razor. On the other hand, by turning the tube 18 in a direction opposite to the first mentioned 10 turning, the clamping member 12 is brought closer to the seat 8 to clamp the blade 9 in place. If it is desired to replace the blade 9 then the tube 18 is turned until the stem 28 is entirely disengaged from the threaded end thereof, thereby 15 permitting the turning of the clamping member 12 into inverted position as shown in Fig. 5. The blade 9 is thus readily accessible and removable from the upwardly projecting stem 28 and a new blade can be placed in position. 20 In order to prevent the entire removal of the guide bars 14 from the seat 8, a stop 29 is threadedly secured on the free end of each bar 14 to abut against the lower face of the seat 8 thereby limiting the upward movement of the clamping member 12 only to a distance sufficient to allow 25 the stem 28 to clear the seat 8 as the member 12 is turned into inverted position. Thus in this safety razor, a razor blade may be replaced without entirely separating the elements 30 of the safety razor from each other.

The blade 9 itself is formed with a lug or grip wing 31 at each end thereof, each extending from a half of the length of the said end, whereby the gripping and handling of the blade 9 is greatly 35 facilitated. The wings 31 extend beyond the ends of the clamping member 12 and the latter is to be turned so that the wingless half of the blade 9 is moved between the guide bars 14, namely, the clamping member 12 is turned in the direction of its edge denoted by the numeral 32, when inverted, and it is rotated in the direction of its edge 33 when it is turned back to normal position. 40 Having thus described this invention, what I claim and desire to secure by Letters Patent is:

45 1. In a safety razor, a blade seat; a handle extending from the under face of the blade seat; a blade holder fitting over the top face of the seat to hold a razor blade interposed between the seat and the holder; a stem on the holder extended into the handle; means in the handle to hold the stem in the handle being adapted to move said stem into and out of said handle respectively to cause the clamping and releasing of the razor blade; and guides related to the holder slidably engaging said seat, said holder being journaled in said guides to permit the inverting thereof for removing and inserting the razor blade on the stem.

50 2. In a safety razor, a blade seat; a blade having cutting edges on opposite sides thereof; a blade cap; a handle extended from the seat; means on the handle to removably secure the cap in place to engage said blade rearwardly of and immediately adjacent its cutting edges to hold said razor blade between the seat and the cap; means slidably through the seat to guide the cap, said cap being journaled in said guides to be turnable into an inverted position.

55 3. In a safety razor, a blade seat; a handle

extending from said seat; a clamping member to engage said blade rearwardly of and immediately adjacent its cutting edges to hold said razor blade between the said member and the seat; means to secure the clamping member in place; and guide elements slidably extended through the seat to guide said member, said member being journaled in said guide elements to be turnable into an inverted position when spaced above the seat.

4. In a safety razor, a blade seat; a hollow handle extending from the underside of the blade seat; a blade holding member above the blade seat to clamp a razor blade interposed between the upper face of the seat and the said member; a threaded stem slidably extending from said member into the end of the handle; an internally threaded tube extending through the hollow handle; means to rotatably hold said tube in said handle so as to prevent axial movement thereof, the threaded end of said tube engaging the threaded stem to move the holding member toward and away from said seat; and a guide bar at each end of the said member slidably extending through the blade seat outside of the ends of the razor blade, said member being rotatably supported at its ends in said guide bars.

5. In a safety razor, a blade seat; a hollow handle extending from the underside of the blade seat; a blade holding member above the blade seat to clamp a razor blade interposed between the upper face of the seat and the said member; a threaded stem slidably extending from said member into the end of the handle; an internally threaded tube extending through the hollow handle; means to rotatably hold said tube in said handle so as to prevent axial movement thereof, the threaded end of said tube engaging the threaded stem to move the holding member toward and away from said seat; a guide bar at each end of the said member slidably extending through the blade seat outside of the ends of the razor blade, said member being rotatably supported at its ends in said guide bars; and a stop on the free end of each bar to limit the movement thereof out of said seat.

6. In a safety razor a blade seat; a handle extending from said seat; a clamping member to hold a razor blade interposed between the said member and the seat; means to secure the clamping member in place; guide elements slidably extended through the seat to guide said member, said member being journaled in said guide elements to be turnable into an inverted position when spaced above the seat; and means on the free ends of the guide elements to prevent the removal thereof from the blade seat.

7. A safety razor, consisting of a blade seat, a blade and a cap to hold the blade on the seat; a stem on the cap adapted to be extended thru the blade and seat to hold the blade between the cap and seat; means on the seat to engage said stem; and slides guided in the seat at opposite ends thereof and having opposite ends of the cap journaled thereon whereby the cap with the blade thereof may be turned into an inverted position when the cap stem is released.

JOHN D. GARRETSON.
